[57] CLAIM

The ornamental design for the electronic game viewing head piece, as shown and described.

DESCRIPTION

FIG. 1 is a perspective view of an electronic game viewing head piece showing our new design;

FIG. 2 is a front elevational view thereof;

FIG. 3 is a rear elevational view thereof;

FIG. 4 is a right side view thereof;

FIG. 5 is a left side view thereof;

FIG. 6 is a bottom plan view thereof; and,

FIG. 7 is a top plan view thereof.

The broken line showing of human figure is for illustrative purpose only and forms no part of the claim.
